UNITED STATES PATENT OFFICE

2,475,091

PIN GRINDING MACHINE

Basil H. Hackman, Waukegan, Ill.

Application April 17, 1947, Serial No. 741,976

16 Claims. (Cl. 51—53)

1

This invention relates to a pin grinding machine and more particularly to such a machine for grinding tapered points on the steel pins which are used in lapping operations in making tungsten carbide wire drawing dies. Heretofore, grinding machines of this nature had to be hand operated and each pin was inserted and removed from the grinding machine by hand, thus resulting in excessive labor costs and slow operation. It was also difficult to change the angle of the taper on the pin.

It is an object of this invention to provide a pin grinding machine which is fully automatic and only requires an operator to place the pins in a feeding hopper and to remove the finished pins from a receiving hopper.

Another object is to provide such a device in which the taper ground on the pin may be readily varied.

These and other objects will be more apparent after referring to the following specification and attached drawings, in which:

Figure 1 is a plan view of the entire machine, with dot-and-dash lines to indicate certain movements;

Figure 2 is a side elevation, partly in section, showing all three spindle positions and operations;

Figure 3 is a view taken on the line III—III of Figure 2 and showing the indexing gears and collet-opening mechanism;

Figure 3A is a view of a part broken out of Figure 3 and showing the bottom of the hopper;

Figure 4 is a plan view, partly in section, of the spindle construction, collet mechanism, and a typical grinding position of the grinder;

Figure 5 is a view of a pin in a pin holder;

Figure 6 is a fragmentary view along line VI—VI of Figure 1;

Figure 7 is a plan view, partly in section, of the fixed collet-opening cam taken on the line VII—VII of Figure 2;

Figure 8 is a view taken on the line VIII—VIII of Figure 2 and showing the face of the indexing pin plate or disk;

Figure 9 is a sectional view taken on the line IX—IX of Figure 10 and showing the turret plates assembled with spacers;

Figure 10 is a view taken on the line X—X of Figure 2;

Figure 11 is a sectional view of the spindle drive taken on the line XI—XI of Figure 12;

Figure 12 is a sectional view taken on the line XII—XII of Figure 11;

2

Figure 13 is a sectional view taken on the line XIII—XIII of Figure 12;

Figure 14 is a diagrammatic view of the air system in relation to the cam position when the plungers are retracted;

Figure 15 is a view similar to Figure 14, but showing the cam position when the plungers are loading and ejecting;

Figure 16 is a view taken on line XVI—XVI of Figure 2 and showing the air system cam and valve when the plungers are in the position shown in Figure 15;

Figure 17 is a view taken on the line XVII—XVII of Figure 2 and showing the grinder cam position at the start of grinding;

Figure 18 is a fragmentary view similar to Figure 17, but showing the grinder cam position when the grinder is retracted from the pin being ground;

Figure 19 is a side elevation, partly in section, of the grinder base;

Figure 20 is a transverse section taken on the line XX—XX of Figure 19.

The following figures are all of the "collet closed" position, with the index pin in the index plate:

Figure 21 is a view taken on the line XXV—XXV of Figure 2 and showing the collet opening cam when the collet closed position and the index pin in the index plate;

Figure 22 is a side elevation of Figure 21;

Figure 23 is a view taken on the line XXV—XXV of Figure 2 and showing the index pin operating cam when in the collet closed position A;

Figure 24 is a side elevation of Figure 23;

Figure 25 is a view taken on the line XXV—XXV of Figure 2 and showing the collet opening cam with the index pin cam set within it when in the collet closed position A;

Figure 26 is a side elevation of Figure 25.

The following figure is in the "collet open" position, and when the index pin is moved outwardly from the index plate:

Figure 27 is a view similar to Figure 25, but showing the position of the cams in the collet open position and the index pin out of the index plate.

Referring more particularly to Figure 1 of the drawings, reference numeral 2 indicates a base on which a grinder 4 and a plate 6 are mounted. The plate 6 is pivotally connected to the base 2 by means of a pin 8 and is held in adjusted position thereon by means of a nut and bolt 10 extending upwardly from the plate 2 through

55

a slot 12 in the plate 6. The entire mechanism with the exception of grinder 4 is mounted on the plate 6. The pins P to be ground are placed in a hopper 14 with their pointed ends directed toward the main portion of the machine. Preferably the pins P are gripped in a holder or chuck 15 as shown in Figure 5. As shown in Figures 3 and 3A, the hopper 14 is made of sheet metal and is provided with a diagonal plate 16 which separates the hopper into top and bottom sections. Adjacent the left hand end of the hopper, as seen in Figure 3, is a baffle plate 18 which assists in directing the pins P into an inclined runway 20 extending along the bottom of the hopper. The lowest point in the hopper is provided with openings 22 at each end thereof which permits the lowest pin in the runway 20 to be discharged from the hopper by means of an air actuated plunger 24 mounted in a cylinder 26. As shown in Figure 1, the cylinder 26 is mounted on a frame 28 bolted or otherwise fastened to the plate 6 and is provided with air conduits 30 and 32, one at each end thereof. An indexing head assembly, carried in a frame 34, is located adjacent the discharge end of hopper 14. The indexing head shaft 36 is mounted in bearings 38 which are supported in the frame 34. As best shown in Figures 2, 9 and 10, two plates 40 are fixed upon shaft 36 in spaced apart relationship and support three collet carrying spindles 42 therebetween. These spindles are positioned 120° apart and are rotatably supported in bearings 44, which in turn are supported by the plates 40. Each of the spindles 42 supports a V-pulley 46 for receiving a friction drive which will be referred to later. As shown, the pulley 46 is integral with the spindles 42, but it will be understood that it may be a separate part secured to the spindles. Plates 40 are held in spaced apart relationship by means of spacers 48. As best shown in Figure 4, each of the spindles 42 is hollow and carries therein a spring loaded collet assembly which includes a tubular collet actuator portion 50 having a threaded end portion which carries a collet actuator nut 52. The outside diameter of the actuator portion 50 is reduced at its left hand end as shown in Figure 4 to enable a collet actuator spring 54 to fit thereover. Spring 54 is maintained under compression at all times by a spring retainer nut 56 which is threaded into the left hand end of the hollow spindle 42. The right hand end of tubular member 50 has an enlarged recessed portion 58 in which is slidably mounted a coil actuator insert 60 which, in turn, receives a standard Ericson collet 62. A collet nut 64 threaded onto the spindle 42 retains the collet 62 in position. In order to open the collet assembly it is necessary to move the tubular member 50 to the left as shown in Figure 4 and thus allow the insert 60 to be forced to the left by the expanding force of the slotted Ericson collet 62. The member 50 is moved by a collet opening slide 66 (Figure 2), slidably supported in the frame 34 by a bushing 68. The slide 66 is provided with an axial opening 70 which is aligned with the openings 22 in the hopper 14 through which the pins P are fed into the collet assembly. A nut 72 is threaded onto the left hand end of slide 66 and is provided with lugs 74 which fit within openings 76 in a lever arm 78. As shown in Figure 3, the lever arm 78 is pivotally supported on a pin 80 with its free end extending downwardly and supporting a cam follower 82 which follows the cam track 84 of a cam 86

mounted on the cam shaft 88. As shown in Figures 21 and 22, the cam track 84 has a 120° high portion A, a 220° low portion B and 20° ramp portions D and C between portions A and B.

Mounted on the shaft 36 adjacent the right hand end thereof (as seen in Figure 2) is an indexing plate 90 which is provided with three equally spaced openings 92 therethrough as shown in Figure 8. The indexing head has three positions, position #1 being the loading position, position #2 being the grinding position, and position #3 being the discharging position. Adjacent position #1 the frame 34 is provided with openings 94 and 96, opening 94 slidably receiving a pin stop 98 and opening 96 slidably receiving a positioning pin 100. As shown in Figure 2, pin stop 98 and positioning pin 100 are threaded over one-half of their lengths and are adjustably secured in a member 102, which in turn is pivotally secured to the upper extremity of a lever arm 104. The lever arm 104 is pivotally supported on a pin 106 mounted on the frame 34 and its lower extremity is flexibly secured to one end of a tie rod 108 which passes through the frame 34 and has its opposite end flexibly connected to a lever 110 located outside of frame 34. A spring 112 surrounds the rod 108 between the lever 104 and the frame 34, thus urging the pin stop 98 and positioning pin 100 to the left. The lever 110 is pivotally mounted on a pin 114 with the free end of the lever extending upwardly and supporting a cam roller 116 which follows the face of a cam 118. The cam 118 is mounted on cam shaft 88 and is held in place thereon by means of a tapered pin 120. As shown in Figures 23 and 24, the cam 118 has a 240° low portion E, an 80° high portion F and 20° ramp portions G and H between portions E and F. As shown in Figures 24, 26 and 27, a hub 122 extends outwardly from the cam 118 and supports the cam 86. Threaded openings 124 are provided in the cam 86 for receiving countersunk screws which pass through openings 126 in the cam 118.

As shown in Figure 1, the cam shaft 88 is driven from a ratio motor 128 through a drive shaft 130 and coupling 132. An indexing gear 134 provided with five teeth is mounted on cam shaft 88 adjacent the cam 118 and a plate 136 is secured thereto by cap screws 138. The plate 136 is circular, but has a reduced diameter through 74°, as shown in Figure 3.

The shaft 36 extends through the frame 34 and has an indexing pinion 140 secured to its left hand end which meshes with gear 134. An indexing plate 142 is secured to the pinion 140 by cap screws 144. In practice, the speed of the motor 128 and the relationship between indexing gear 134 and indexing pinion 140 is such that the indexing gear 134 will mesh with the pinion 140 every thirty seconds to advance the entire indexing assembly 120° to its next position. Cams 86 and 118 are so positioned on shaft 88 with respect to the indexing gear 134 that the pin stop 98 and positioning pin 100 will be withdrawn just prior to the meshing of the teeth on gear 134 with the teeth on pinion 140 and the collet opening slide 66 will be held in position to prevent the opening of the collet until an empty collet has been presented thereto at the end of 120° of travel from the ejecting position. The plate 142 has three concave portions 146 on its outer periphery, the radius of each portion being equal to the radius of the outer periphery of plate 136 so that plates 136 and

142 will mesh with respect to each other and afford a secondary means for maintaining the indexing head assembly in any one of its three positions.

When the indexing head with the pin P therein is advanced to position #2, its V-pulley 48 contacts a driven Bakelite friction wheel 148, which is keyed or pinned to a gear 150 as shown in Figure 12. The wheel 148 and gear 150 are fastened to a shaft 152 supported in bearings 154 which are mounted in rocker plates 156. The gear 150 meshes with a gear 158 which is rotatably mounted on a shaft 160 and is held in its desired position thereon by means of hollow shafts 162 and 164. The hollow shafts are fixed to the shaft 160 by means of screws 166 passing through the outer ends thereof. The hollow shafts 162 and 164 are mounted in a spindle stand 168 and are held from rotation thereon by means of set screws 170. The spindle stand 168 is fastened to the plate 6 by means of cap screws 172. The rocker plates 156 are pivotally supported on bushings 174 mounted on the hollow shafts 162 and 164. Brackets 176 are fastened to the bottom of the friction wheel assembly and a bolt 178 extends outwardly therefrom and supports a plate 180. Screws 182 pass through the plate 180 and are screwed into the spindle stand 168. A spring 184 surrounds each of the bolts with one end bearing against a nut 186 and the other end against the plate 180, thus providing for a yielding contact of the wheel 148 and the pulley 48. The gear 158 meshes with a gear 188 fixed to the shaft of motor 190.

After the pin to be ground is advanced to position #2 of the indexing head and the spindle 42 is rotating, the grinding operation is started. As shown in Figures 1 and 4, the grinder motor 192 carries a grinding wheel 194 at the end of its shaft 196. As shown in Figures 19 and 20, the motor 192 is mounted on a plate 198 which in turn is slidably supported by a saddle 200 by means of four ball bearings 202 which are confined in a pair of trackways 204. The saddle 200 is slidably gibbed to the grinder slide base 206 which is fixedly secured to the base plate 2 by means of bolts 208. A bolt 210 passes through slots 212 in the saddle 200 and is provided with nuts 214 bearing against the sides of the saddle to hold it in position. As shown in Figure 1, the bolt 210 is threaded into a member 216 which is pivotally connected to a lever 218 mounted on a bolt 220 fastened to plate 6. The other end of lever 218 is pivotally connected to one end of an arm 222, the other end of the arm 222 being bifurcated to receive the central portion of a link 224 which is fastened thereto by means of a pin 226. One end of the link 224 is pivotally secured to the frame 34 by means of a bolt 228 and the other end carries a cam follower 230 which follows the track of a cam 232 which is fastened to shaft 88. Movement of the grinder in a direction parallel to the point of a pin is accomplished through a ratio motor 234, shaft 236, eccentric disk 238 and link 240 which is connected to the motor 192 by means of a bolt 242. The ratio motor 234 is an electric motor used in connection with a gear reducer with its shaft 236 extending upwardly. The upper end of the shaft 236 has the eccentric disk 238 connected thereto with the connecting bar 240 being pivotally connected to one of two holes 244 in the eccentric disk 238, the holes being at different distances from the center of the disk 238 to provide for adjustment of the length of the

stroke of the grinder. The cam 232 brings the grinder into contact with the pin P on its 240° dwell portion and out of contact on the remaining 120°. The movement of the cam 232 is timed with the movement of the pin positioning the pin stop cam 118 whose 240° dwell portion holds the pin positioning pin 100 and the stop pin 98 in the position shown in Figure 2, thereby holding the indexing head in position while the grinding of the pin is taking place during the 240° dwell of the grinder cam 232. The grinder moves away from the pin during the 40° fall of cam 232 and toward the pin during the 80° rise. While the grinder is moving away, cam 118 causes the positioning pin and pin stop to move outwardly and allow the indexing head to be advanced 120° by the partial gear 134. As the indexing head moves through 120° the spindle which was previously in position #2 advances to position #3 and as it comes into this position the collet actuator nut 52 contacts a fixed cam 248 (Figure 2) which urges it outwardly, thus removing the compressive force of spring 54 against the tubular section 58 which retains the Ericson collet 62 in a closed position. Therefore, when spring 54 is compressed, collet 62 is allowed to expand and free the pin P.

As shown in Figures 14 to 16, a four-way air valve 248 is mounted adjacent the cam shaft 88 with its valve stem 250 extending toward a cam 252 fastened to the cam shaft 88. A cam roller 254 is carried by a yoke 256 secured to the end of a yoke stud 258 which in turn is slidably supported in a bearing 260. The valve 248 and bearing 260 are mounted on top of a bracket 262. An air cylinder 264 (Figure 2) is mounted adjacent the frame 34 which is provided with an opening 266 in line with the collet in position #3. A plunger 268 is actuated by cylinder 264 and moves forward into the spindle opening 70 to eject the pin contained therein as soon as the collet 62 releases the pin which falls into a receiving pan 270. The air cylinder 264 is provided with conduits 272 and 274 at opposite ends thereof.

45. The operation of the device is as follows: Pins P are placed in the hopper 14 as shown in Figures 1 and 3. The plate 6 is turned on its pivot 8 to provide the right taper for the pin being ground and is then locked in place by means of the bolt and nut 10. The motors 128, 190, 192 and 234 are started in operation. This starts the cam shaft 88 rotating and with it the cams mounted thereon. Cam 252 is so arranged that when an empty collet reaches position #1 the four-way valve 248 is moved to admit air into the left hand end of cylinder 264, thus enabling the plunger 268 to shove the bottom pin P out of the hopper 14 through the opening 70 into the collet 62 which grips the pin. At the same time, cam 118 will move the pin stop 98 and positioning pin 100 into the position shown in Figure 2, thus locking the indexing head in position and positioning the pin P in the correct axial position. Also, at the same time, the cam 232 causes the lever 218 to rotate about its pivot 220 and move the grinder against the pin P in position #2, this motion being at right angles to the surface to be ground. As described hereinbefore, the grinding wheel 194 will be in contact with the pin on the 240° dwell portion of the cam 232. Motor 234 through its associated mechanism will reciprocate the grinding wheel 194 to grind the surface of the pin P. Meanwhile the collet in position #3 will have been opened by contact of the nut 52 on the cam 248. Also at the same time air will be admitted

through conduit 272 to force the machined pin P in position #3 out of the collet and into the pan 270. Continued movement of the cam 252 changes the position of the four-way valve 248 to introduce air into the right hand end of cylinders 26 and 264 to retract their respective plungers. It will be understood that during the grinding operation the collet in position #2 will be rotated by means of the pulley 46 contacting the wheel 148. After the grinding operation has been completed, continued movement of the cam 118 retracts the pin stop 98 and positioning pin 100. Meanwhile the indexing gear 134 has rotated until the teeth thereon meshes with the teeth of pinion 140, thus rotating the indexing head through 120°. The indexing head is then in position to receive another pin P from the hopper 14 and the operation is repeated.

While one embodiment of my invention has been shown and described it will be apparent that other adaptations and modifications may be made without departing from the scope of the following claims.

I claim :

1. A grinding machine for grinding a taper on pins comprising a base, a grinder mounted on said base, a plate adjacent said grinder pivotally mounted on said base adjacent said grinder, a frame mounted on said plate, a shaft rotatably mounted in said frame with one end extending therefrom, an indexing head mounted on said shaft for movement therewith to three different positions, said positions being the loading, grinding and discharge positions, three collets arranged on said indexing head in spaced apart relationship with their axes parallel to the axis of said shaft, jaws associated with each collet for gripping one of said pins, a rotatable cam shaft, a cam mounted on said cam shaft for opening said jaws at the loading position, means for feeding a pin axially into said collet at the loading position, a second cam mounted on said cam shaft for actuating said feeding means after the jaws of the collet at the feeding position are open, said first named cam causing said last named jaws to close after the pin is fed therein, a pinion mounted on the extended end of the indexing head shaft, a partial gear mounted on said cam shaft and adapted to mesh with said pinion to rotate the indexing head at intervals from position to position, means for rotating the collet in the grinding position, means for opening the jaws of the collet at the discharge position, and means for discharging the pin from the collet at the discharge position.

2. A grinding machine for grinding a taper on pins according to claim 1 in which a hopper is provided adjacent the feeding means for receiving said pins, said hopper having an axial opening through the bottom thereof in line with the axis of said collet, said feeding means including a rod adapted to reciprocate in said axial opening.

3. A grinding machine for grinding a taper on pins according to claim 2 in which a stationary cam is mounted on said frame to actuate the jaw opening means at the discharge position.

4. A grinding machine for grinding a taper on pins according to claim 3 in which the second cam on said cam shaft actuates the discharge means after the jaws of the collet at the discharge position are opened.

5. A grinding machine for grinding a taper on pins according to claim 4 having means for moving the grinder against the pin, a third cam mounted on said cam shaft for actuating the

grinder moving means when a collet reaches the grinding position.

6. A grinding machine for grinding a taper on pins according to claim 5 having movable means limiting the axial movement of the pin at the loading position and a fourth cam mounted on said cam shaft for actuating the said limiting means when a collet reaches the loading position.

7. A grinding machine for grinding a taper on pins according to claim 6 having an indexing plate mounted on the indexing head shaft, said indexing plate having three spaced apart openings therein with their axes parallel to the axis of the indexing head shaft, said frame having an opening in said frame adjacent the loading position, a pin, means for moving said pin through said last named opening into one of the openings in the indexing plate, said fourth cam actuating said pin moving means at the same time as it actuates the said limiting means to lock the indexing head in position.

8. A grinding machine for grinding a taper on pins according to claim 1 in which a stationary cam is mounted on said frame to actuate the jaw opening means at the discharge position.

9. A grinding machine for grinding a taper on pins according to claim 8 in which the second cam on said cam shaft actuates the discharge means after the jaws of the collet at the discharge position are opened.

10. A grinding machine for grinding a taper on pins according to claim 9 having means for moving the grinder against the pin, a third cam mounted on said cam shaft for actuating the said pin moving means when a collet reaches the grinding position.

11. A grinding machine for grinding a taper on pins according to claim 10 having movable means limiting the axial movement of the pin at the loading position and a fourth cam mounted on said cam shaft for actuating the said limiting means when a collet reaches the loading position.

12. A grinding machine for grinding a taper on pins according to claim 11 having an indexing plate mounted on the indexing head shaft, said indexing plate having three spaced apart openings therein with their axes parallel to the axis of the indexing head shaft, said frame having an opening in said frame adjacent the loading position, a pin, means for moving said pin through said last named opening into one of the openings in the indexing plate, said fourth cam actuating said pin moving means at the same time as it actuates the said limiting means to lock the indexing head in position.

13. Indexing mechanism for positioning pins for machining which comprises a frame, a shaft rotatably mounted in said frame with one end extending therefrom, an indexing head mounted on said shaft for movement therewith to at least three different positions, said positions being the loading, machining and discharge positions, at least three collets arranged on said indexing head in spaced apart relationship with their axes parallel to the axis of said shaft, each of said collets having an axial opening therethrough, jaws associated with each collet for gripping one of said pins, a rotatable cam shaft, a cam mounted on said cam shaft for opening said jaws at the loading position, means for feeding a pin axially into said collet at the loading position from the rear end thereof with the pin being moved to the correct axial position, a second cam mounted on said cam shaft for actuating said

feeding means after the jaws of the collet at the feeding position are open, said first named cam causing said last named jaws to close after the pin is fed therein, a pinion mounted on the extended end of the indexing head shaft, a partial gear mounted on said cam shaft and adapted to mesh with said pinion to rotate the indexing head at intervals from position to position, means for rotating the collet in the machining position, means for opening the jaws of the collet at the discharge position, and means for discharging the pin from the collet at the discharge position.

14. Indexing mechanism according to claim 13 in which a stationary cam is mounted on said frame to actuate the jaw opening means at the discharge position.

15. Indexing mechanism according to claim 14 in which the second cam on said cam shaft actuates the discharge means after the jaws of the collet at the discharge position are opened.

16. A grinding machine for grinding a taper on pins comprising a grinder, a frame adjacent said grinder, a shaft rotatably mounted in said frame with one end extending therefrom, an indexing head mounted on said shaft for movement therewith to a plurality of positions, said positions including the loading, grinding and discharge positions, at least three collets arranged on said indexing head in spaced apart relationship with their axes parallel to the axis of said shaft, each of said collets having an axial opening therethrough, jaws associated with each collet for gripping one of said pins, a rotatable cam shaft, a cam mounted on said cam shaft for opening said jaws at the loading position, means for feed-

ing a pin axially into said collet at the loading position from the rear end thereof with the pin being moved to the correct axial position, a second cam mounted on said cam shaft for actuating said feeding means after the jaws of the collet at the feeding position are open, said first named cam causing said last named jaws to close after the pin is fed therein, a pinion mounted on the extended end of the indexing head shaft, a partial gear mounted on said cam shaft and adapted to mesh with said pinion to rotate the indexing head at intervals from position to position, means for rotating the collet in the grinding position, means for opening the jaws of the collet at the discharge position, and means for discharging the pin from the collet at the discharge position.
